W. J. REILLY

MATTING

Filed Nov. 29, 1920

Inventor
William J. Reilly

By his Attorney

Therefore I am well

UNITED STATES PATENT OFFICE.

WILLIAM J. REILLY, OF NEWARK, NEW JERSEY.

MATTING.

Application filed November 29, 1920. Serial No. 426,980.

To all whom it may concern:

Be it known that I, WILLIAM J. REILLY, a citizen of the United States, residing at Newark, in the county of Essex and State 5 of New Jersey, have invented certain new and useful Improvements in Matting, of which the following is a specification, reference being had therein to the accompanying drawing.

10 My invention relates to improvements in matting, and more particularly has reference to matting formed of links or small sections of material hinged together in continuous formation, forming strips or runners, 15 such as are adapted for use in halls, restaurants, public places, and the like. One of the principal objects of my invention is to provide a simple and durable method of strengthening the matting at the ends without reinforcing rods, and if desirable at 20 points along the length of the matting to insure proper rigidity and durability.

In the accompanying drawings, I have illustrated in Fig. 1 in plan view, partly 25 broken away, a suitable form of mat embodying an application of my invention. Fig. 2 is an end view looking upwardly at Fig. 1. Fig. 3 is a view looking rightwardly at Fig. 1, and Figs. 4 to 7 inclusive are dia- 30 grammatic views of different forms of links.

The end links such as 8 are preferably longer as shown in Fig. 4, and are pierced by pintle rods or wires such as 9—9' which 35 preferably are bent over at the ends adjacent each other and secured by suitable means such as the sleeve wristlets 10. Alternate groups of the links are preferably shorter as indicated at 11 and shown to better advantage in Fig. 5 so as to allow for 40 the recessing and linking up of adjoining

links 12 as shown. This provides a rigid end of sufficient body to remain flat upon the floor and resist side kicks and buckling in wear, such as usually occurs when precautions for reinforcing, etc., are not provided. 45 As a further provision, I also prefer to insert at different points along the mat, other sections of elongated links such as indicated at 8', thus reinforcing the matting sufficiently throughout its length to insure 50 against bending up or buckling of the same, while in use, and between these longer links such as 8', the shorter links 13 shown to better advantage in Fig. 6, may be employed, the smaller links such as 14 being shown to 55 better advantage in Fig. 7.

Of course it will be understood that various modifications may be made in the construction and arrangement of parts without departing from the spirit of the invention as claimed. 60

I claim:

In a mat of the class described, groups of links extending in one direction and alternating groups of links therebetween extending in the opposite direction, a tie rod passing through said groups at their overlapping portions, and between said groups a series of longer links in parallel relation with groups of shorter links therebetween, the 65 projecting ends of the longer links and the projecting ends of the first mentioned links overlapping and being secured by a tie rod thereby providing a runner or mat having substantially solid rows of links at intervals 70 throughout the length of the same. 75

In testimony whereof I hereunto affix my signature.

WILLIAM J. REILLY.
